CLAIM

The ornamental design for a corner shaping file, as shown and described.

DESCRIPTION

FIG. 1 is a front, top and side perspective view of the corner shaping file showing my new design;

FIG. 2 is a front elevational view thereof;

FIG. 3 is a rear elevational view thereof;

FIG. 4 is an end elevational view thereof, the end opposite being a mirror image of the end shown in FIG. 4;

FIG. 5 is a top plan view thereof; and,

FIG. 6 is a bottom plan view thereof.

FIG.1

FIG. 2

FIG. 3

FIG. 5

FIG. 6

FIG. 4
